UNITED STATES PATENT OFFICE.

PERCY B. CAMP, OF MAYWOOD, ILLINOIS, ASSIGNOR TO UNIVERSAL DRAFT GEAR ATTACHMENT COMPANY, A CORPORATION OF ILLINOIS.

UNCOUPLING DEVICE FOR RAILWAY CARS.

Application filed April 12, 1923. Serial No. 631,640.

To all whom it may concern:

Be it known that I, PERCY B. CAMP, citizen of the United States, and resident of Maywood, county of Cook, and State of Illinois, have invented certain new and useful Improvements in an Uncoupling Device for Railway Cars, of which the following is a specification and which is illustrated in the accompanying drawings, forming a part 10 thereof.

This invention relates to car coupling devices and more particularly to the uncoupling mechanism or devices for lifting the coupling or locking pins of couplers employed for connecting the cars of railway trains and the like.

One of the objects of the invention is the provision of a new and improved connecting member that is so constructed that it will 20 permit relative movement, in both a horizontal and a vertical plane, between the operating crank and the coupler pin.

Other objects of the invention are the provision of a connecting member that is cheap 25 to manufacture, easily assembled, simple in construction, composed of but few parts, and one that is not likely to break or get out of order.

Other and further objects and advantages 30 of the invention will appear from the following description, taken in connection with the accompanying drawings, in which—

Fig. 1 is a side elevation of a portion 35 of a car and a coupler associated therewith showing one embodiment of my invention applied thereto;

Fig. 2 is a front elevation thereof;

Fig. 3 is an elevation of the device showing the parts extended;

Fig. 4 is a view at right angles from that 40 shown in Fig. 3, showing the parts contracted or telescoped;

Fig. 5 is a section on line 5—5 of Fig. 3; and

Fig. 6 is a perspective of one of the lifting 45 members.

Referring to the drawings in detail, the 50 numeral 10 designates a car, 11 the dead wood or buffer block secured to the front end thereof, and 12 the draw bar associated therewith, all of which is the usual or well known construction. The draw bar 12 is provided with the usual coupler 13 that is adapted to be held in operative position by 55 means of the coupler or locking pin 14.

The locking pin 14 is provided with an extension at its upper end which is apertured as at 15. Journaled in the members 16 and 17, secured to the end of the car 10, is the uncoupling lever 18. The lever 18 is 60 provided at one end with a downwardly extending handle 19 which is adapted to extend to the side of the car and at its other end with laterally extending arm 20 apertured as at 21, as is usual in such constructions. 65

A suitable lifting element for connecting the arm 20 to the pin 14 is provided. This element is so constructed that it will permit lateral, longitudinal and vertical movement 70 of the coupler and car relatively to each other, and at the same time permit rotary movement of the uncoupling lever to lift the pin 14 to unlock the coupler 13. As shown, this lifting element comprises two 75 coupler members or links 22 and 23 that are slidably or telescopically connected together. In order that the cost of manufacture may be reduced to a minimum each member may be formed from a wire or rod 80 of a suitable diameter simply by bending the rod to the desired shape or form. Each member comprises a body portion 24 that is formed by bending the one end of the rod back upon itself to form a slot or loop 85 25, the end of the rod being bent as at 26 to form a closure for the outer end of the slot 25. Each of the body portions 24 is provided with grooves 27 on each side of the return bend. The grooves 27 are in 90 alignment with the slots 25 so that when the body portions of the coupler members 22 and 23 are interlinked the side members forming the slots 25 of one of the body members will engage the grooves in the 95 other body member to thereby prevent pivotal movement of one member relatively to the other, but at the same time permitting the coupler members 22 and 23 to telescope or slide one upon the other. 100

The outer ends of the coupler members or links 22 and 23 are bent to form the eyes 28 and 29 respectively. The eyes 28 and 29 are left open so that they may engage in the openings 21 and 15 in the arm 105 20 and pin 14.

When a chain with the usual type of links is employed as a lifting element it is necessary that the links connected to the operating lever and the locking pin be closed in 110

order to prevent their becoming detached by the bumping, jarring and shaking of the car and coupler incident to their travel. In the present device the members 22 and 23 5 cannot pivot relatively to each other, consequently the attaching eyes 28 and 29 are preferably left open whereby the lifting element may be readily and easily attached to both the lifting arm 20 and the coupler 10 pin 14, during the assembling of the parts. When the parts are assembled, however, the lifting element cannot be removed without first removing the pin or the lifting lever from its assembled position. When 15 the parts are in assembled relation as shown in Figs. 1 and 2, it is evident that the lifting element will not accidentally become disengaged or be likely to be surreptitiously removed.

20 It will be observed that the body portions of the two coupler members or links are exact duplicates of each other, and that the eye members 28 and 29 are arranged in the same plane. The eye members are arranged in the same plane in order to accommodate apertures in the arm 20 and the 25 pin 14 which in the ordinary construction are arranged with their axes parallel. It is understood however that the members 30 22 and 23 may be made exact duplicates of each other, and this would be desirable in order to cheapen the manufacturing cost. But in the coupling mechanism as now constructed, the axes of the apertures 21 35 and 15 in the arm 20 and the coupler pin 14 are parallel to each other, consequently it is necessary that the eyes 28 and 29 be arranged in the same plane. It is understood however that they may be arranged 40 otherwise.

It is thought from the foregoing taken in connection with the accompanying drawings that the construction and operation of my device will be apparent to those skilled 45 in the art, and that various changes in size, shape, proportion and details of construction may be made without departing from the spirit and scope of the appended claims.

I claim as my invention:

50 1. A locking pin lifting element, comprising a member having one end bent to form an attaching eye and its other end bent to form a loop, and a second member having one end bent to form an eye and 55 its other end bent to form a loop threaded through the loop of said first named mem-

ber, the planes of said loops being arranged at an angle to each other and one of said members being provided with means for engaging the other for preventing relative pivotal movement of said members. 60

2. A locking pin lifting element comprising a rod bent to form an eye at one end and an elongated loop at the other, a second rod having one end bent to form an eye and its other end bent to form an elongated loop interlocking with the first named loop, the return bend of each loop being provided with recesses at opposite sides thereof for engaging the sides of the 70 other loop to prevent pivotal movement between said loops.

3. A locking pin lifting element comprising two members, each formed from a single rod, said members having duplicate 75 interlinked loop-shaped body portions, one of said members being provided with a groove for engaging the other member for preventing pivotal movement between said sections, and attaching means secured to the outer ends of said members.

4. A locking pin lifting element, comprising a plurality of comparatively straight body members having elongated slots therein, said members being interlinked whereby one of said members may slide on the other, and being provided with means for preventing pivotal movement of one member relative to the other. 85

5. A locking pin lifting element, comprising a plurality of body members having elongated slots therein, said members being interlinked, and each body member being provided with grooves at each side thereof for engaging the other member 95 whereby said members are slidably but non-rotatably connected to each other.

6. In combination, a car coupler including a coupler pin provided with an aperture through one end thereof, an uncoupling member including an arm having an aperture through its outer end, the axes of said apertures extending in the same direction, and a lifting element comprising two members having their adjacent ends inter-linked and slidably and non-rotatably connected together, said members having their interlinked portions comparatively straight throughout their entire length, the outer ends of said members being provided with 100 open eyes for engaging in said apertures. 110

PERCY B. CAMP.
